FIRE SCREEN

Frederick G. Wallenta, Stratford, Conn.

Application June 3, 1941, Serial No. 396,387

7 Claims. (CL. 160—363)

This invention relates to fire place constructions, and particularly to a fire screen that is adapted to be built into the fire box of a fire place, and one that contains no parts that are apt to wear out, break or require adjustment during the life of the structure.

Fire screens of the built-in type have heretofore included relatively complicated structures for counterbalancing their weight to maintain them at desired elevations. Others provide complicated roll mechanisms for rolling the screen to effect its elevation. All of these prior-known built-in fire screens contain mechanism that frequently breaks, gets out of order or wears out, requiring substantial dismantlement of the entire fire place in order to repair the screen and its attending mechanism.

An object of this invention is to provide a built-in fire screen that overcomes the above and other difficulties attending the use of prior-known fire screens.

Other objects of the invention include the provision of a fire screen that can be maintained at any desired elevation without employing counterweights, roll mechanism, etc.; the provision of a fire-place screen that contains no moving parts that are apt to break, require repair or adjustment; the provision of a fire-place screen which is adapted to be held at desired elevations by means providing friction between tracks and screen, and which is effective throughout the entire travel of the screen; and the provision of a fire-place screen adapted to slide in tracks, portions of each of which tracks are in different planes.

The above, other objects and novel features of the invention will become apparent from a consideration of the following specification and accompanying drawing, in which:

Figure 1 is a front elevational view of a fire place including a fire screen embodying the principles of this invention;

Figure 2 is a sectional elevational view taken substantially along line 2—2 of Fig. 1;

Figure 3 is a partial sectional plan view taken substantially along line 3—3 of Figure 2; and

Figure 4 is a sectional elevational view of a modification of the structure shown in Figure 2.

Referring to Figure 2, the fire place comprises a fire box 10 including a throat portion 11 that is formed by a lintel 12 anchored in opposite side walls of the fire box. Walls 13 and 14 extend upwardly from the throat 11 and form a flue 15. As shown in Figure 2, the construction provides

a substantial space 16 between the wall 17 of the room and the wall 13 of the flue 15.

A space 18 (Figs. 2 and 3) at the mouth of the fire box 10 is adapted to receive a track member 19. The track 19 is of generally channel shape with flanges 20 located along its side walls. The space 18 is adapted to be filled with cement in which track member 19 is adapted to be securely anchored.

10 The track member 19 is adapted to extend vertically upwardly to a point 21 above the lintel 12 where it is curved, extending into space 16. The upper extremity of track 19 is connected to a cross member 22 that is likewise connected to the top 15 of an identical track member at the opposite side of the fire box 10. The cross member 22 is securely fixed to the wall 13 of flue 15 by cementing or otherwise. Accordingly, the lower portions of track members 19 are securely fastened to opposite walls of the fire box 10 by the cement in the spaces 18, and the upper portions of said track members are maintained in fixed position by cross bar 22.

25 A relatively heavy wire screen 23 is fastened at its lower end to a rigid cross member 24. The opposite ends of the cross member 24 are adapted to fit and slide within the channels of track members 19. Additionally, the screen 23 is provided with relatively stiff selvaged edges that likewise 30 ride within the channels of track members 19. The length of the screen 23 is such that a portion of its selvaged edges at all times cooperate with the curved portion 21 of the tracks 19. The curvature 21 of tracks 19 is sharp enough to provide sufficient friction between it and the screen to 35 maintain the screen at any elevation to which it is moved. However, the curvature 21 is gradual enough to permit sliding of the screen along the tracks 19 when the same is raised by grasping handles 25 fixed to cross member 24.

40 The fire place is finished off in the usual manner by providing a mantle 26, tile 27 and finishing members 28. The tiles 27 are set in the cement within spaces 18 and effectively cover the track members 19.

45 Referring to Figure 4, a modification of the invention is disclosed wherein the wall 29 of the flue 15 is so constructed that relatively little space is provided between it and the room wall 17. In this form of the invention, each track member 19 is provided with a curvilinear portion 30 between two portions that lie in the same plane. In this form, as in that shown in Figure 2, the length of screen 23 is such that a portion of its selvaged 50 edges always cooperates with the curvilinear por-

tion 30 of each track 19, thereby providing friction between it and the screen to maintain the latter at all times at any desired elevation.

Although the principles of the invention have been described in detail to illustrate two forms of the invention, it is evident that changes may be made in such details, and certain features may be used without others without departing from the principles of the invention.

What is claimed is:

1. A fire screen for a fire place comprising in combination, a track member adapted to be secured along a side wall of a fire box; a flexible screen having a selvaged edge adapted to fit within said track member; said track member having means providing a concentrated frictional engagement with successive small portions only of said selvaged edge when said screen is raised and lowered to thereby maintain at least a substantial portion of said screen at any desired elevation.

2. A fire screen for a fire place comprising in combination, a track member adapted to be secured along a side wall of a fire box, extending from the hearth thereof to a point substantially above the lintel of said fire box and having a portion in a different plane from the remainder and a relatively-sharp curvilinear portion joining the portions in different planes; and a flexible screen having a side edge located within said track, a portion of said edge being at all times in engagement with said relatively-sharp curvilinear portion, said relatively-sharp curvilinear portion only of said track providing sufficient friction between said screen and track member to maintain at least a substantial portion of said screen in any desired elevation.

3. In a fire place construction, a track member adapted to be secured along a side of a fire box, including a substantially vertically-disposed portion and an angularly-disposed portion joined thereto by a relatively-sharp connecting member; and a flexible screen having a side edge adapted to ride in said track member, the edge of said screen being at all times in cooperative engagement with said connecting member, the relatively-sharp portion only thereof providing sufficient friction between the track and said screen to maintain at least a substantial portion of said screen in any desired position.

4. In a fire place construction, a track member adapted to be secured along a side of a fire box, the length of said track member being substantially greater than twice the vertical dimension of said fire box from the hearth to the lintel thereof; said track member including a substantially vertical portion extending from the bottom to a point above the lintel of said fire box, the remainder of said track member being joined to said vertical portion by a relatively-sharp connecting portion; and a flexible screen having a side edge adapted to ride freely in said track member, a portion of the screen being at all times in cooperative engagement with the relatively-

sharp connecting portion of said track member, whereby sufficient friction is provided between said edge and said connecting portion to maintain at least a substantial portion of said screen at any desired elevation.

5. In a fire place construction, a continuous track member having a length greater than substantially twice that of the vertical dimension of the opening of said fire place between its hearth and lintel, a portion of which track is substantially straight and a portion of which is sharply curved relatively to said straight portion; a part of the straight portion of said track member being adapted to be secured to the wall forming the opening of said fire place; a flexible screen having an edge adapted to ride freely in the straight portion of said track member, a portion of said edge of the screen being at all times in cooperative engagement with the sharply curved portion of said track member, whereby sufficient friction is provided between said edge and said sharply curved portion only of said member to maintain at least a substantial portion of said screen at desired elevations.

25 6. In a fire place construction, a track member adapted to be secured along a side of a fire box, the length of said track member being substantially greater than twice the vertical dimension of said fire box from its hearth to its lintel; said track member including substantially straight-line separated portions joined by a relatively-sharp curvilinear portion; and a flexible screen having an edge adapted to ride freely in said separated track portions, a portion of said edge of said screen being at all times in cooperative engagement with the relatively-sharp curvilinear portion of said track member, whereby sufficient friction is provided between said edge and said relatively-sharp curvilinear portion only to maintain at least a substantial portion of said screen at desired elevations.

45 7. In a fire place construction having a fire box; a flue therefor and a wall substantially flush with the outer extremity of said fire box and spaced from said flue; a track member located adjacent said wall and fire box and including a portion extending from the bottom of said fire box upwardly in a single plane to a point above the top of said fire box; an additional portion 50 of said track member extending upwardly within the space between said flue and wall, and lying in a plane at an angle to the first-mentioned portion of said track member; a relatively-sharp curvilinear portion joining said angularly-related track portions; and a flexible screen having an edge adapted to ride freely in said track portions, said edge being at all times in cooperative engagement with said sharp curvilinear joining portion, whereby sufficient friction is provided 55 between said edge and said curvilinear portion only to maintain at least a substantial portion of said screen at desired elevations.

FREDERICK G. WALLENTA.
